United States Patent Office

Des. 232,855
Patented Sept. 17, 1974

232,855

TOY SCOOP

Jorma Vennola, Princeton, N.J., assignor to Columbia
Broadcasting System, Inc.

Filed Feb. 16, 1973, Ser. No. 333,359

Term of patent 14 years

Int. Cl. D21—01

U.S. Cl. D34—15 V

FIG. 1

FIG. 2

FIG. 3

FIG. 4

FIG. 5

FIG. 1 is a side perspective view of a toy scoop showing my new design;

FIG. 2 is a top plan view thereof;

FIG. 3 is a bottom plan view thereof;

FIG. 4 is a front elevational view thereof; and

FIG. 5 is a side elevational view thereof.

I claim:

The ornamental design for a toy scoop, substantially as shown.
